MAGNETIC SEPARATOR

René Planiol, New York, N. Y., assignor to Pluro, Inc., New York, N. Y., a corporation of New York

Application September 21, 1945, Serial No. 617,711

23 Claims. (Cl. 209—223)

1

The present invention relates to the art of magnetic separation, that is of separating magnetic from non-magnetic particles of fine granular or powdered ore or other comminuted stock.

It is among the objects of the invention to provide a method and compact apparatus for continuously performing such method, expeditiously and effectively to segregate the magnetic from the non-magnetic particles of comminuted, such as powdered ore or other stock, even though of sticky or tacky character, without the likelihood of jamming or clogging, or the need for interrupting the operation to clear the mechanism.

In the accompanying drawings in which are shown one or more of various possible embodiments of the several features of the invention, Fig. 1 is a view in longitudinal cross-section showing the right half only of one embodiment of the equipment with parts broken away.

Fig. 1a is a fragmentary detailed view showing the air tight housing.

Fig. 2 is a transverse cross sectional view taken on line 2—2 of Fig. 1.

Fig. 3 is a transverse cross sectional view taken on line 3—3 of Fig. 1.

Fig. 4 is a transverse cross sectional view taken on line 4—4 of Fig. 1.

Fig. 5 is a fragmentary sectional view indicating the approximate magnetic flux and the trajectory of the magnetic and of the non-magnetic particles in the traverse thereof through the machine, the length of the air gap being greatly exaggerated and the feed rotor being omitted for clarity of disclosure, and

Fig. 6 is a fragmentary sectional view similar to Fig. 1, showing a modification.

Referring now to the drawings, the machine comprises a magnet structure, preferably an electromagnet, presenting a pair of annular elements 10 and 11, U-shaped in radial cross-section, abutting at their outer rims and spaced at their inner rims to define an air gap G therebetween.

The two elements of the magnet field structure, the upper of which houses the coil C, are desirably secured together by more or less conventional flange pieces 12 and 13 about their respective rims, which are bolted together as at 14 to maintain an interposed gasket g under compression.

The magnet has an upper annular pole 15 desirably relatively flat, and a lower pole preferably formed as a series of concentric, relatively sharp annular ridges 16, 17, 18, each being in radial cross-section in the form of an isosceles triangle with a relatively rounded apex. The an-

2

nular ridges 16, 17, 18 are identical in radial cross-section but of progressively larger radii, and are substantially spaced from each other. The upper relatively flat annular upper hole 15 extends across all of the ridges of the lower pole. The magnetic flux is thus asymmetrical, that is, the flux density is considerably less at the upper pole than at the apex of each lower pole ridge, so that soft iron magnetic particles reaching the air gap are drawn downward. The magnetic flux is distributed substantially as indicated in the fragmentary view of Fig. 5, to determine a plurality of spaced concentric annular magnetic fields rising from the respective annular pole ridges 16, 17, 18. The electromagnet is desirably constructed to afford a flux through the gap G of the maximum practical intensity, i. e. of about 10,000 Gauss.

According to the invention, the stock to be separated is hurled outward by centrifugal force radially across the air gap C of the magnet. To this end, a feed rotor 20 is provided, which comprises a horizontal plate 21 having a rim 22 near the inner annular magnetic pole ridge 16 and which is at a level slightly above the apex of said ridge and well below the upper pole 15. The rotor is desirably mounted on the upper end of an upright hollow driving shaft 23 extending axially through the magnet structure, lodged in ball bearings 24 and 25, and driven from a suitable source of power (not shown), as for instance through a pulley 26 about the lower end of the said shaft 23.

A pole shield 27 guards the lower pole piece from direct engagement by the magnetic particles. The pole shield is a ring desirably but not necessarily of non-magnetic material, preferably metal affixed at its hub 28 to the end of a hollow shaft 29 which desirably encloses the shaft 23 previously described, turns in ball-bearings 30, 31, and is driven by a suitable source of power (not shown), as for instance through pulley 34 on its lower end. The pole shield extends obliquely upward from its hub past the beveled edge 21 of feed rotor 20 and has a thin horizontal annular web 32 extending over and bridging between the annular pole ridges 16, 17, 18 of the lower pole, said shield having a skirt 33 extending over the outer face of the outer pole ridge 18. The ridge bridging web 32 of the pole shield 27 is preferably substantially in the plane of the feed rotor plate 21.

To segregate the magnetic particles deflected by the action of the pole ridges 16, 17, 18 from the non-magnetic particles hurled outward by the

feed rotor without such magnetic deflection, an interceptor ring 35 is provided. That interceptor ring is a conical wall about the outer pole ridge 18, presenting an upper sharp edge 35' substantially at the level of the feed rotor plate 21.

The interceptor cone is preferably secured at its lower edge upon the upper edge of a cylindrical median wall 36 constituting a unitary part of the magnetic frame structure below the pole. Radial walls 37 connect the median wall to the inner and to the outer walls of the magnet structure and are integral therewith. The magnet thus presents a cellular structure at its lower part, with sector-shaped cells including an inner tier 38 within the wall 36 and an outer tier 39 about the wall 36. The magnetic particles will thus be directed by the interceptor cone 35 into the inner tier of cells 38 and thus segregated from the non-magnetic particles which will pass into the outer cells 39 for removal from the machine in manner to be described below.

The stock of magnetic powder such as iron or iron ore and of non-magnetic powder such as clay to be separated is frequently somewhat adhesive or sticky in character. Means are therefore provided to prevent the separated particles from adhering to the wall of the equipment. To this end, skirt 33 of the pole shield rotor is provided with a series of unitary triangular vanes 40, the outer oblique edges 41 of which substantially run across the inside of the interceptor 35. Likewise the feed rotor 20 is desirably provided with a unitary flat flange 42 extending outward radially across the width of the lower pole ridges 16, 17 and 18 and across the interceptor cone 35 substantially to the outer wall of the magnet pole structure. The flange 42 mounts at the lower face thereof a series of vanes 43 which have an upright outer wall moving along the bore of the magnet structure and an inclined inner wall 44 moving along the outer face of the interceptor cone. Desirably both the said vanes 40 and 43 are in planes inclined to the vertical so that in the rotation of the respective parts the material will not only be loosened but urged downward into and through the respective cells 38 and 39.

The feed rotor is desirably a hollow conical structure comprising the circular plate 21 and a flat hollow cone 45 coaxial therewith and connected thereto by radial fins 46. The hollow cone defines a narrow nozzle at the periphery 22 of plate 21, and the flange 42 extends outward from the cone above said nozzle.

Collector means is provided for the segregated magnetic and non-magnetic particles and convenient means for withdrawing the same from the machine. To this end an annular drum 47 may be disposed directly under the magnet structure and affixed thereto as at 48. This annular drum has a floor 49, an inner wall 50, and an outer wall 51, the latter desirably flush with the magnet structure. In the drum there is desirably mounted a rotor comprising an upstanding annular median wall 52, said wall having an upstanding peripheral fin 53 preferably telescoped into the correspondingly bifurcated lower edge of the magnet dividing wall 36. The rotor wall 52 is desirably provided with a plurality of blades 55 extending to the inner periphery of the drum and blades 56 to the outer periphery thereof. Said inner blades are connected by bridge piece 57 to a shaft 58 mounted on ball bearings 59, 60 coaxial with shafts 23 and 29, and driven as by a pulley 61. The floor of the drum has an outlet 62 at one side of the rotor wall 52 for dis-

charge of the magnetic particles therethrough and a similar outlet 63 at the other side of the annular wall 52 for discharge of the non-magnetic particles. The blades 55 and 56 are preferably inclined to the vertical, positively to push the collected material through the respective ports 62 and 63.

To avoid interfering with the efficacy of separation at the pole piece by the effect of the turbulence of air at that region, the machine is desirably kept under a vacuum applied by a suitable pump (not shown) as through a port 64 in the magnet wall. Such vacuum operation is advisable where the grains of powder to be separated are smaller than 100 microns.

Although any suitable outer air tight housing could be used to contain the unit in order that a vacuum may be maintained, in the embodiment herein shown the housing illustratively comprises a casing 72' positioned over the feed 72 and a casing 62' enclosing the ports 62 and 63.

Since the stock is frequently relatively adhesive in character, the introduction of an air blast for disintegrating such stock would not ordinarily be practical where, as preferred, it is desired to operate the machine under vacuum. Therefore, the present invention affords a means for effecting such separation without the introduction of air or gas. To this end, desirably a centrifugal disintegrator plate 65 is provided. This plate is of relatively small diameter and is co-planar with the feed rotor plate 21, it being desirably countersunk within a central opening 66 in the plate 21. The disintegrator plate is desirably mounted on the upper end of an inner shaft 67 encircled by shaft 23, said inner shaft rotating in ball bearings 68 and 69 and being driven by suitable means, as by a pulley 70. The disintegrator plate 65 may, if desired, have narrow ribs 71 to facilitate operation. The hopper 72 from which the stock to be treated is introduced, feeds through pipe 73 directly upon the disintegrator plate 65 which is driven at relatively high speed, effectively to disintegrate the lumped masses of particles.

For clarity, the method of the present invention and the mode of operation of the illustrative equipment for carrying such method into execution will now be described.

The stock drops by gravity upon the disintegrator plate 65 which is rotated at speed such as to cause any small lumps of iron and clay for instance, to become disintegrated as they are hurled outward toward the feed rotor 20. By the feed rotor, the stock thus previously disintegrated is hurled outward centrifugally at high speed through the peripheral nozzle at 22 in an annular stream of small thickness across the annular air gap G. In this movement, as will be apparent, the magnetic flux to the innermost of the annular pole ridges 16 selectively deflects the magnetic particles downward somewhat, without in any wise however affecting the movement of the non-magnetic particles. As the stream is hurled past the second magnetic pole ridge 17, the deflected magnetic particles are further deflected downward, and thus the operation proceeds as the stream of particles flows past the successive magnetic ridges (which would be of suitable number) until, by the time the final outer magnetic pole ridge 18 is passed, the deflection will be sufficient for the knife edge 35' of the interceptor cone 35 to intercept the magnetic particles and allow the remaining particles to proceed therebeyond.

The non-magnetic pole shield rotor 27 prevents the magnetic particles from adhering to the pole ridges 16, 17, 18. It is driven at such speed that it imparts sufficient centrifugal force to any particles in contact therewith to hurl the same outward along skirt 33 for release at the lower part of such skirt, where there is substantially no magnetic field.

The machine operates sufficiently with a high output, since the succession of annular magnet pole ridges makes possible a sufficient deflection of the magnetic particles in their traverse across the radius of the air gap, even though the feed rotor is revolved at the tremendous speed necessary for a large output with consequent high centrifugal force.

Fig. 5 shows the approximate trajectories of the non-magnetic particles (shown in dot and dash lines) and of the magnetic particles (shown in dotted lines), the length of the magnetic gap G between the poles being greatly exaggerated.

Thus the magnetic particles released from near the lower edge of skirt 33 will drop into the inner tier of cells 38 in the magnet structure while the non-magnetic particles that had not been deflected downward will drop into the outer tier of cells 39, the vanes 40 on the skirt of the pole shield 27 and the vanes 43 on the flange 42 of the feed rotor assisting the downward movement of the segregated particles and precluding adhesion thereof to the respective wall structures. The separated particles pass downward into the drum 47 and the annular collectors therein at opposite sides of the rotor ring 52. In the slow propulsion of the collector rotor 52 from the pulley 61, the collected material is swept out of the machine into suitable receptacles (not shown), the magnetic particles through port 62 and the non-magnetic through port 63.

It will of course be understood that equipment with as many or as few of the concentric magnet pole ridges 16, 17, 18, as desired, may be employed. In Fig. 6 is shown illustratively a fragment of equipment like that of Fig. 1, except that the lower pole piece has but a single annular ridge 16'. The machine would have a correspondingly lower output, since the centrifugal force applied to the stock must not be so high that the single pole ridge would fail to effect sufficient deflection for reliable segregation of the magnetic particles.

As previously indicated, the vacuum operation is preferred, since this avoids the entrainment of non-magnetic with magnetic particles due to eddy currents of air near the air gap under the speed of centrifugal propulsion. Where such vacuum is applied, it will be understood that each of the bearings is equipped with a suitable oil seal of more or less conventional construction, such as those illustratively shown, where raw hide-impregnated straps 74 are held by coil springs 75 against the coacting bearing surfaces.

In a typical small machine, according to the present invention, where the diameter of the annular air gap G is say 15 centimeters and the width of the gap might be 1 centimeter, the feed rotor 20 would be operated at a speed of 2500 or more R. P. M.; the pole shield rotor 27 might be operated at a speed of 6000 R. P. M. or more, and the disintegrator rotor plate 65 at a speed of 3000 R. P. M. or more.

The machine and method are not limited to the separation of magnetic from other solid particles but may be used to advantage for the sep-

eration of magnetic particles from a stream of gas entraining the same as, for instance, immediately following the reduction of iron ore. In this case it will be apparent that the magnetic particles will be separated exactly as above described and the great bulk of the gas will pass outward from beyond the interceptor cone 35. If the gas is propelled under suitable pressure, the feed rotor 20 could be left stationary in such operation, as will be immediately apparent.

As many changes could be made in the above method and construction, and many apparently widely different embodiments of this invention could be made without departing from the scope of the claims, it is intended that all matter contained in the above description or shown in the accompanying drawings, shall be interpreted as illustrative and not in a limiting sense.

Having thus described my invention, what I claim as new and desire to secure by Letters Patent of the United States is:

1. A magnetic separator, comprising an electromagnet having an annular air gap with a lower pole of higher flux density and an upper pole of lower flux density, a feed rotor encompassed by said poles and at level slightly higher than that of the lower pole, non-magnetic rotary shield plate over said lower pole, and an interceptor ring encompassing said lower pole and having an upper edge substantially at the level of said rotary shield plate, and collectors below said interceptor ring and at opposite sides thereof, respectively, for the magnetic and the non-magnetic components.

2. A magnetic separator, comprising an electromagnet having a cylindrical outer wall and an inner wall with an upper relatively flat annular pole and a lower relatively sharp annular pole with an annular air gap therebetween, a feed rotor encompassed by said air gap and at level slightly higher than that of the lower pole, an interceptor ring having an annular upper edge substantially at the level of said feed rotor and encompassing the lower pole piece, an annular wall mounting said interceptor ring for segregation of the non-magnetic particles at one side thereof and the magnetic at the other, vanes interposed between the interceptor ring and the inner and outer walls of the magnet structure, and means for rotating said vanes to force the separated particles downward for collection thereof.

3. A magnetic separator, comprising an electromagnet structure, having a cylindrical outer wall and a generally cylindrical inner wall having a relatively flat upper annular pole piece and a relatively sharp lower annular pole piece determining an annular air gap therebetween, a feed rotor encompassed by said air gap and at level slightly higher than that of the lower pole piece, a non-magnetic shield cap rotor extending over the lower pole, an upstanding cylindrical dividing wall within the electromagnet between the outer and inner walls of the latter, and an interceptor cone supporting on top of said dividing wall and having an upper separator edge near said shield cap rotor and substantially at the level of the feed rotor, inclined vanes interposed between the interceptor cone and the outer wall of the electromagnet, inclined vanes interposed between the interceptor cone and the shield cap rotor, and means for revolving said vanes about the axis of the separator.

4. The combination recited in claim 3, in which the vanes at the outer side of the interceptor cone are rigid with the feed rotor.

5. The combination recited in claim 3, in which the vanes at the inner side of the interceptor cone are rigid with the shield cap rotor.

6. A magnetic separator, comprising an electromagnet structure having a cylindrical outer wall and a generally cylindrical inner wall, the latter having a relatively flat upper annular pole piece and a relatively sharp lower annular pole piece determining an annular air gap therebetween, a feed rotor encompassed by said air gap presenting an annular nozzle adjacent said air gap and at level slightly higher than the lower pole piece, said rotor including an annular flange extending outward from the upper edge of said nozzle to nearly the inner face of the outer wall of the magnet structure, an interceptor ring about the air gap at substantially the level of the feed rotor, a series of inclined vanes rigid with the lower face of said flange and interposed between the interceptor ring and the outer wall of the casing, a non-magnetic shield cap rotor coaxial with said feed rotor and extending with small clearance along the lower pole piece and a series of inclined vanes affixed to the outer portion of said shield cap and rotating therewith along the inner wall of the interceptor ring.

7. A magnetic separator, comprising a generally cylindrical hollow electromagnet shell, having a continuous cylindrical outer wall and an interrupted interior wall presenting an upper pole piece, a lower pole piece of greater flux density and an annular air gap therebetween, means for introducing the stock axially of the separator, a feed rotor at level slightly higher than that of the lower pole piece, an interceptor ring having an upper edge at substantially the level of said rotor and intercepting magnetic particles subjected to both magnetic and centrifugal action, while passing non-magnetic particles subjected only to centrifugal action.

8. A magnetic separator of the type claimed in claim 7, encased under vacuum, and means for breaking the adhesion between particles preliminary to the separator action, said means comprising a small rotor plate encompassed by the feed rotor and at substantially the level thereof.

9. A magnetic separator, comprising an electromagnet casing structure having a cylindrical outer wall, annular pole pieces spaced inward therefrom with an annular air gap therebetween, the upper of said pole pieces being relatively flat and the lower relatively sharp, a plurality of upright coaxial drive shafts encompassed by the electromagnet, one of said drive shafts having a feed rotor affixed thereon, said rotor presenting a horizontal plate extending at its periphery near and slightly above the lower pole piece and encompassed thereby, one of said drive shafts having a non-magnetic shield cap rotor thereon extending in part under said feed rotor, and over and along the effective outer area of the lower pole piece.

10. A magnetic separator, comprising an electromagnet casing structure having a cylindrical outer wall, annular pole pieces spaced inward therefrom with an air gap therebetween, the upper of said pole pieces being relatively flat and the lower relatively sharp, a plurality of upright coaxial drive shafts encompassed by the electromagnet casing, one of said drive shafts having a feed rotor affixed thereon, said rotor presenting a horizontal plate extending at its periphery near and slightly above the lower pole piece and encompassed thereby, a second of said drive shafts having a non-magnetic shield cap rotor thereon

extending in part under said feed rotor and capping the lower pole piece and extending along its effective outer area, and a third of said drive shafts having a rotor disk substantially at the level of and encompassed by the feed rotor, and a hopper introducing the stock to drop upon said disk.

11. A magnetic separator, comprising an electromagnet casing structure, having a cylindrical outer wall, annular pole pieces spaced inward therefrom with an air gap therebetween, the upper of said pole pieces being relatively flat and the lower relatively sharp, a plurality of upright coaxial drive shafts encompassed by the electromagnet, one of said drive shafts having a feed rotor affixed thereon, said rotor presenting a horizontal plate extending at its periphery near and slightly above the lower pole piece and encompassed thereby, a second of said drive shafts having a non-magnetic shield cap rotor thereon extending in part under said feed rotor, capping the lower pole piece and extending along its effective outer area, generally annular separator cells between the inner and outer walls of the electromagnet and below the pole pieces thereof, said cells having a cylindrical separator wall concentric and between the inner and outer walls of the electromagnet, and an interceptor ring rising from the upper end of said separator wall and having an upper edge at substantially the level of the shield cap.

12. A magnetic separator, comprising an electromagnet casing structure, having a cylindrical outer wall, annular pole pieces spaced inward therefrom with an air gap therebetween, the upper of said pole pieces being relatively flat and the lower relatively sharp, a plurality of upright coaxial drive shafts encompassed by the electromagnet, one of said drive shafts having a feed rotor affixed thereon, a second of said drive shafts having a non-magnetic shield cap rotor thereon extending in part under said feed rotor, capping the lower pole piece and extending along its effective outer area, generally annular separator cells between the inner and outer walls of the electromagnet and below the pole pieces thereof, said cells having a cylindrical separator wall concentric with and between the inner and outer walls of the electromagnet, an interceptor ring rising from the upper end of said separator wall, and having an upper edge at substantially the level of the shield cap, said feed rotor comprising a flat hollow conical structure presenting a thin peripheral nozzle, near and slightly above the lower pole piece, said conical structure having a flat flange above the nozzle extending over the lower pole piece and its cap shield, over the interceptor ring and substantially to the outer wall of the electromagnet casing.

13. A magnetic separator, comprising an electromagnet casing structure having a cylindrical outer wall, annular pole pieces spaced inward therefrom with an air gap therebetween, the upper of said annular pole pieces being relatively flat and the lower relatively sharp, a plurality of upright coaxial drive shafts encompassed by the electromagnet, one of said drive shafts having a feed rotor affixed thereon, a second of said drive shafts having a non-magnetic shield cap rotor thereon extending in part under said feed rotor, capping the lower pole piece and having a skirt over its outer face, separator cells in the electromagnet and below the pole pieces thereof, a cylindrical dividing wall through said cells concentric with and between the inner and outer

walls of the electromagnet, an interceptor ring rising from the upper edge of said dividing wall, having an upper edge at substantially the level of the shield cap, said feed rotor comprising a flat, hollow conical structure determining a thin peripheral nozzle encompassed by the air gap, said conical structure having a flat outstanding flange above the nozzle extending over the lower pole piece, its cap shield and the interceptor ring and substantially to the outer wall of the electromagnet casing, and inclined vanes respectively on the skirt of the shield cap rotor and on the underwall of the outstanding flange, said vanes respectively clearing the inner wall of the interceptor ring and the inner surface of the outer wall of the electromagnet.

14. A magnetic separator, comprising an electromagnet structure, having a cylindrical outer wall, a generally cylindrical inner wall presenting an annular relatively flat upper pole piece and an annular relatively sharp lower pole piece, both spaced from the top and bottom of the electromagnet structure, the lower part of the electromagnet structure below the lower pole piece presenting radiating ribs and a median annular wall, defining segment shaped cells, a collector drum directly under the electromagnet structure, an annular separator wall in said drum directly below the median annular wall, defining annular collector receptacles, and discharge ports from opposite sides of the annular separator wall, means for centrifugally hurling the stock across the annular air gap, an interceptor ring adjacent the lower pole piece and encompassing the same, having its upper edge at substantially the level thereof, for directing the magnetic particles toward the inlet side thereof through the inner magnet cells to the corresponding inner collector receptacle and for hurling the non-magnetic particles through the outer cells to the corresponding outer collector receptacle.

15. The combination recited in claim 14, in which the annular separator wall is rotatably mounted, in which drive means constantly revolves the same and in which vanes unitary with and at opposite sides of said separator wall are rotated therewith and break adhesion of the particles with the respective walls, the discharge ports being in the bottom of the drum.

16. In a magnetic separator, an electromagnet structure, consisting of two annular pieces each generally U-shaped in radial cross-section and secured in abutting relation at their outer rims, the inner annular edges of the structure being spaced and defining poles, the upper of which is relatively flat and the lower relatively sharp, the lower of said electromagnet pieces having longitudinal cells therethrough below the pole piece, said cells comprising an inner tier and an outer tier, a cylindrical separator wall of the magnetic structure between said tiers, and an interceptor wall rising from said separator wall and presenting an upper edge encompassing and slightly above the lower pole.

17. A magnetic separator comprising an electromagnet structure consisting of two annular pieces, each generally U-shaped in radial cross-section and secured in abutting relation at their outer rims, the inner annular edges of the structure being spaced and defining pole pieces, the upper of which is relatively flat and the lower relatively sharp, the lower of said electromagnet pieces having longitudinal cells therethrough below the pole piece, said cells comprising an

inner tier and an outer tier, a cylindrical dividing wall of the magnetic structure between said tiers, a conical interceptor well rising from said dividing wall and presenting an upper edge encompassing and slightly above the lower pole piece, means for introducing the stock axially downward through the annular electromagnet structure, a plurality of rotors for treating said stock at substantially the level of the air gap, up-right shafts coaxially through the structures for driving said rotors, said rotors including a feed rotor with its periphery near the air gap and slightly above the lower pole, and a shield cap rotor over the lower pole piece.

18. A magnetic separator comprising an electromagnet structure, said structure consisting of two annular elements each generally U-shaped in radial cross section and secured in abutting relation at their outer rims, the inner annular edges of the respective elements defining spaced pole pieces, the upper of which is relatively flat and the lower relatively sharp, the lower of said elements having longitudinal cells therethrough below the pole piece thereof, said cells comprising an inner tier and an outer tier, a cylindrical dividing wall of the magnetic structure between said tiers, an interceptor cone rising from said wall and presenting an upper edge encompassing and slightly above the lower pole piece, means introducing the stock axially downward through the annular electromagnet structure, a plurality of rotors for treating said stock substantially at the level of the air gap, upright shafts extending coaxially through the annular magnetic structure for driving said rotors, said rotors including a feed rotor with its periphery near the air gap and slightly above the lower pole, a shielding pole cap rotor over the lower pole piece, a collector drum coaxial with and immediately below the electromagnet structure, said drum having an annular rotor therein, comprising a median wall extending the height of the drum and telescoped with respect to the lower edge of the dividing wall of the magnet, said median wall having vanes rigid therewith extending to the opposite faces of the drum, drive means coaxial with the rotor drives for slowly driving said annular rotor within its drum, said drum having ports in its floor at opposite sides of the median wall of the rotor therein for discharge of the segregated magnetic and non-magnetic material therefrom.

19. A magnetic separator, comprising an electromagnet structure consisting of two annular elements, each generally U-shaped in radial cross-section and secured in abutting relation at their outer rims, the inner annular edges of the respective annular elements defining spaced pole pieces, the upper of which is relatively flat and the lower relatively sharp, and defining an air gap therebetween, the lower of said elements having longitudinal cells therethrough below the pole pieces, said cells comprising an inner tier and an outer tier, a cylindrical dividing wall of the magnetic structure separating said tiers, an interceptor cone rising from said dividing wall and presenting an upper edge encompassing and slightly above the lower pole piece, means for introducing the stock axially downward through the annular electromagnet structure, a plurality of rotors for treating said stock substantially at the level of the air gap, concentric upright shafts axially through the magnet for driving the several rotors, said rotors including a feed rotor with its periphery near the air gap and slightly above

the lower pole, a shielding pole cap rotor over the lower pole piece, a flat rotor plate substantially in the plane of and encompassed by the inner periphery of the feed rotor, an annular collector drum coaxial with and immediately below the magnet, said drum having an annular rotor therein with a median wall extending the height of the drum and telescoped with respect to the lower edge of the dividing wall of the magnet, said annular rotor having vanes rigid therewith extending to the opposite faces of the drum, drive means coaxial of the rotor drives for slowly driving said annular rotor within its drum, said drum having outlet ports in its floor at opposite sides of the median wall for discharge of the segregated magnetic and non-magnetic material therefrom.

20. A magnetic separator, comprising an electromagnet structure having coating annular elements each U-shaped in radial cross-section, abutting at their outer rims and presenting spaced annular pole pieces at their inner periphery including a relatively flat upper pole piece and a relatively sharp lower pole piece, the lower magnet structure below the pole piece thereof being longitudinally cellular and including two tiers of cells having radiating walls and having a cylindrical dividing wall, an interceptor cone rising from said dividing wall and having an upper edge encompassing and slightly above the lower pole piece, means for introducing the stock axially and longitudinally through the magnet structure, and a series of rotors for handling the material, said rotors comprising a feed rotor and a shielding cap rotor, concentric shafts driving the respective rotors, the feed rotor hurling the stock peripherally outward and the shielding cap rotor precluding adhesion of the magnetic material to the pole, and a drum coaxially of the structure disposed directly under the magnet, having a rotor therein, presenting an annular wall registering with the dividing walls, vanes rigid with said annular wall and adjacent the respective inner and outer walls of said drum and drive means concentric with the rotor drives for slowly moving the annular rotor about its axis, said drum having ports in the floor thereof for discharge of the segregated batches of magnetic and non-magnetic material.

21. A magnetic separator comprising a pair of annular magnet elements each U-shaped in

5
10

radial cross-section determining a cylindrical outer wall and spaced annular pole pieces at its inner wall, defining an air gap therebetween, an interceptor ring about said air gap, the upper of said pole pieces being relatively flat and the lower of said pole pieces comprising a plurality of spaced concentric relatively sharp annular ridges, a feed rotor encompassed by said lower pole piece and presenting a rim adjacent the inner of said annular pole ridges and slightly above the level thereof, and a non-magnetic pole shield rotor coaxial with said feed rotor and extending across the width of said lower annular pole piece and the several annular ridges thereof.

15
20
25
30

22. The combination recited in claim 21, in which the feed rotor comprises a hollow wide based cone, presenting a thin annular nozzle about the base thereof and in which said cone has a unitary flat flange extending outward substantially to the wall of the electromagnet structure, and in which the base of the electromagnet has a cellular structure including a cylindrical dividing wall between the inner and the outer magnet structure and in which an interceptor cone rises from said wall and presents an edge substantially at the level of and closely contiguous to the pole shield rotor.

23. The combination recited in claim 2 in which means are provided affording an air tight seal in said air gap and about said rotor whereby a vacuum may be created in which said rotor may revolve.
